Louis Steinberger, INVENTOR
Cornelia M. Billings, BY
Harold G. Coker, ATTORNEY

UNITED STATES PATENT OFFICE.

LOUIS STEINBERGER, OF BROOKLYN, NEW YORK.

TELEPHONE RECEIVER.

1,366,606.

Specification of Letters Patent. Patented Jan. 25, 1921.

Application filed February 27, 1919. Serial No. 279,530.

To all whom it may concern:

Be it known that I, LOUIS STEINBERGER, a citizen of the United States, and a resident of the borough of Brooklyn, city and State of New York, have invented certain new and useful Improvements in Telephone Receivers, of which the following is a specification.

My invention relates to telephone receivers wherein variations in the current flowing through a talking telephone circuit produce changes in the magnetic flux emanating from a magnet, with concomitant changes in the force exerted by the magnet upon a vibratory soft iron diaphragm operated thereby.

One of the objects of my invention is to provide an improved construction of receiver wherein the vibrations set up in the air by the vibrating diaphragm upon each of its sides are utilized to set up sound waves which pass to the ear of the listener whereby a better speech reproducing effect is secured.

Another object of my invention is to provide an improved receiver wherein the diaphragm is more free to vibrate than has heretofore commonly been the case, such end following from the equalization of the air pressure upon two sides of the diaphragm which is a feature of the improved telephone receiver wherein my invention consists.

Another object of my invention is to provide a receiver construction by means of which air passages extend from one side of the diaphragm to the other.

Another object of the invention is to provide a receiver construction by means of which required air passages may be readily formed from the moldable material of which either the cap or the casing is made.

Another object of my invention is to provide a cap structure for a telephone receiver having an annular air space inclosed therein adjacent the periphery of the diaphragm.

Another object of my invention is to provide a cap structure for a telephone receiver having an annular air space inclosed therein adjacent the periphery of the diaphragm, and conduits leading from said air space to each side of the diaphragm.

Other objects will appear from the subjoined specification and claims.

Referring to the drawings forming a part of this specification in which:

Figure 1 is a view, for the most part in section, upon a central longitudinally extending plane of a telephone receiver embodying my invention. 60

Fig. 2 is a view showing a section of the cap portion upon a transverse plane indicated by line 2—2 of Fig. 1.

Fig. 3 is a view showing one end of a modified construction of the casing of the 65 receiver in side elevation.

Fig. 4 is a plan view of the modification of the casing shown in Fig. 3.

Fig. 5 is a plan view of the casing shown in Fig. 1. 70

In the drawing in which the same reference character indicates the same part in the several views, 5 designates the exterior casing of a telephone receiver, the same being made either of electrose, hard rubber or 75 similar non-metallic insulating material, and having an open end across which the vibratory soft iron diaphragm 6 extends. The diaphragm is held in place by a cap 7 made of material similar to that of which the 80 casing is made and having a threaded connection therewith at 8 apart from the diaphragm, whereby a chamber 9 is provided between the cap 7 and the diaphragm 6, as clearly shown in Fig. 1. 85

In the preferred embodiment of my invention as shown in Fig. 1, a hollow cup shaped shell 12 of metal is located within and conforming generally with the shape of the upper interior portion of the casing, the 90 open end of which is closed by the diaphragm 6, whereby an internal chamber 13 is provided between the diaphragm and the shell. The open end of the shell 12 is provided with the circumferentially radially 95 extending flange 14 which is situated a short distance from the upper end or face 15 of the casing 5, as the shell 12 is so shaped that the conical portion 16 rests on the inner wall of the casing at 17, as shown. 100

When the shell is in place within the casing the periphery of the diaphragm 6 rests upon the flange 14 of the shell and is clamped thereupon by the cap when secured to the screw threads at 8, as shown. Holes 105 or perforations 18 are provided in the wall of the shell and are so located as to approximately extend between the upper face 15 of the casing and the underside of the flange 14 and thus establish a plurality of communications between the interior of the shell constituting the chamber 13 and the circum-

ferentially extending internal groove, recess or passage 19 formed within the cap 7, at the periphery thereof.

As a modified construction the open end 5 of the casing 5 may be mutilated, that is, may be provided with a lug or preferably with a plurality of lugs or teeth 10 spaced apart one from the other and arranged throughout the circumference of the open 10 end thereof, as clearly shown in Fig. 3, thus forming openings 11 therebetween which lead from the chamber 13 through the holes 18 to the recess 19, as will be understood from the drawing. It is preferable, however, and in the interest of simplicity of 15 construction and elimination of costs in construction to make the upper face 15 of the casing 5 smooth, thereby eliminating the formation of lugs thereupon.

20 The cap 7 is provided with a lug or series of internal lugs or teeth 20 so arranged as to abut against the diaphragm 6 and clamp it in place on the flange 14 of the shell 12, that is, the free ends of these lugs or teeth 25 engage the perimeter of the diaphragm and hold the parts thereof together when the receiver is assembled and secured to the casing at 8, as will be understood. The spaces 21 thus formed between the lugs or 30 teeth 20 are then in communication with the chamber 9 between the end wall of the cap and the front side or face of the diaphragm, and also with the passage 19 in the cap whereby a permanently open air passage is 35 provided from the chamber 9 at the front side of the diaphragm to the chamber 13 at the underside of the diaphragm through the holes 18, as shown.

In the event that the structure shown in 40 Fig. 3 is used the air passages will also be provided through the spaces 11 between the lugs 10 through the holes 18 to the chamber 13, all as will be understood, as the spaces between the teeth are in communication 45 with the chamber 13 through the holes 18.

By means of either of these two constructions, preferably that shown in Fig. 1, or in the modified construction shown in Fig. 3, it will be readily understood that 50 the chamber on the underside of the diaphragm is in communication with the chamber on the upper side of the diaphragm and to the atmosphere through the permanently open air passage 0 in the wall of the cap. 55 Of course, it will be understood that a single passageway from one side of the diaphragm to the other is all that is absolutely necessary, but it is preferable to provide more than one of such passageways. In the 60 embodiment of my invention as shown, I have provided a plurality thereof which are ordinarily present and which, as clearly seen, extend outwardly in a radial direction to the edge of the diaphragm and then 65 downward and past or around the edge

thereof and then inward radially to the chamber 13, as will be appreciated.

The magnetic elements of the receiver are shown conventionally at 30, 31 and 32, and may be of any suitable form as my invention is in no way concerned with the details 70 of the magnet whereby the diaphragm is caused to vibrate.

As changes of construction could be made within the scope of my invention it is intended that all matter contained in the above description or shown in the accompanying drawings shall be interpreted as illustrative and not in a limiting sense.

Having now described my invention, what 80 I claim as new and desire to secure by Letters Patent is:

1. In a telephone receiver, a suitable casing having an open end, a cap in engagement with the open end of said casing having a series of spaced lugs or teeth upon its inner surface, and having an annular channel outside of said lugs or teeth.

2. In a telephone receiver, a suitable casing having an open end, a series of spaced lugs or teeth arranged about said open end, a cap in engagement with the open end of said casing and having a series of spaced lugs or teeth upon its inner surface and so arranged as to lie opposite the teeth at the 95 open end of said casing, a vibratory diaphragm the periphery of which is held in place between the teeth upon said casing and the teeth upon said cap, the said cap having formed therein a circumferentially extending groove with which the spaces between the teeth or lugs upon both said casing and said cap communicate.

3. In a telephone receiver, a suitable casing having an open end and a sloping inner 105 wall extending from and below said open end, a vibratory diaphragm extending entirely across the open end of said casing, a hollow shell seated on said sloping wall and extending beyond the open end of said 110 casing and having an open end across which said diaphragm extends whereby an internal chamber is provided upon the rear face of said diaphragm, a cap secured to the open end of said casing and having an end wall 115 spaced apart from said diaphragm whereby a chamber is provided between the said end wall and the front face of said diaphragm, and a permanently open air passage extending from one of said chambers around the 120 edge of the diaphragm and into the other chamber, the said diaphragm being held in place between the cap and the upper face of said casing.

4. In a telephone receiver, a suitable casing having an open end, a series of spaced lugs or teeth arranged about said open end, a hollow shell located within said casing and having an open end, a peripherally extending flange resting upon the free ends of the 130

teeth aforesaid, a cap in threaded engagement with the open end of said casing and having a series of spaced lugs or teeth upon its inner surface and so arranged as to lie opposite the teeth at the open end of said casing, a vibratory diaphragm the periphery of which is held in place between the flange aforesaid and the teeth carried by said cap, a circumferentially extending groove provided within said cap at the periphery thereof and with which the spaces between the teeth or lugs upon both said casing and said cap communicate, and holes provided in the wall of said hollow shell and so arranged as to communicate with the spaces between the teeth at the open end of said casing.

5. In a telephone receiver, a suitable casing having an open end, a cap in threaded engagement with the open end of said casing having a series of spaced lugs or teeth upon its inner surface, and having an annular channel outside of said lugs or teeth.

6. In a telephone receiver, a suitable casing having an open end, a cap in threaded engagement with the open end of said casing having a series of spaced lugs or teeth upon its inner surface, of a vibratory diaphragm, a shell situated within the upper end of the casing provided with openings therein situated above the upper end of the casing, a vibratory diaphragm the periphery of which is held in place between the teeth or lugs upon the said cap and the upper end of the said shell, the said cap having provided therein a circumferentially extending groove with which the spaces between the teeth or lugs of the cap and the openings in the shell communicate.

7. In a telephone receiver, a cap provided with means for engagement with the casing, said cap being mutilated upon its inner sur-

face, said mutilations forming air passages therebetween, and an air space in said cap outside of said mutilated surface with which said air passages communicate.

45

8. In a telephone receiver, a vibratory diaphragm, a cap and a casing, means for securing the cap, diaphragm and casing together, said cap having an annular chamber formed within the wall thereof, and means for establishing air communication between said chamber and the central portion of said cap, when it is secured to said casing.

50

9. In a telephone receiver, a cap, diaphragm and casing, means for securing the same together, the said cap having a chamber provided therein on one side of the diaphragm, the casing having a chamber provided therein on the other side of the diaphragm, the cap being provided with a groove or chamber at the periphery of the diaphragm, said chambers having air communications therebetween.

55

10. In a telephone receiver, a cap, diaphragm and casing, means for securing the same together, the said cap having a chamber provided therein on one side of the diaphragm, the casing having a chamber provided therein on the other side of the diaphragm, the cap being provided with a groove or chamber at the periphery of the diaphragm, said chambers being connected for the passage of air therethrough to each side of the diaphragm.

60

11. In witness whereof, I have hereunto set my hand at the borough of Manhattan, city and State of New York, this 19th day of February, 1919.

65

LOUIS STEINBERGER.

In presence of:—

C. C. BILLINGS.
